(57) **CLAIM**

The ornamental design for a remote terminal unit in oil and gas production environments, as shown and described.

DESCRIPTION

FIG. 1 is front perspective view of the remote terminal unit in oil and gas production environments showing our new design; FIG. 2 is a front elevation thereof; FIG. 3 is a rear elevation thereof; FIG. 4 is a right side elevation thereof; FIG. 5 is a left side elevation thereof; FIG. 6 is a top plan view thereof; FIG. 7 is a bottom plan thereof; FIG. 8 is a rear side perspective view thereof; FIG. 9 is a top front perspective view thereof; FIG. 10 is a bottom front perspective view thereof; and, FIG. 11 is a bottom rear perspective view thereof.

The broken line showing of the remote terminal unit is for the purpose of illustrating environmental structure and forms no part of the claimed design.
